UNITED STATES PATENT OFFICE.

CHESTER W. ACKERMAN, OF BAINBRIDGE, OHIO, ASSIGNOR OF TWO-FIFTHS TO ROBERT L. RUSSELL AND ONE-FIFTH TO HALBERT J. THRASHER, BOTH OF CHARDON, OHIO.

FUEL-SUPPLY TANK.

Application filed December 9, 1926. Serial No. 153,714.

This invention relates to fuel supply tanks for internal combustion engines, and more particularly to a fuel supply tank internally equipped with a carburetting apparatus, and 5 instrumentalities so connecting the tank and motor that, under the aspirations of the latter, a carburetted mixture of high efficiency will be automatically delivered to the motor for combustion.

10 In the utilization of the structure embodying my invention, the usual form of carbureter is eliminated, and the carburetting device is positioned directly within the fuel supply tank. A valve controlled air pipe 15 leads into the tank, as does also the manifold of the motor, and, during the operation of the motor, air is drawn into the tank and through the gasoline contained therein, the mixed air and gasoline then being subjected 20 to such carburetting action that a mixture of high efficiency passes into the manifold and to the motor.

It is therefore the object of the invention to combine with a fuel supply tank or reservoir, 25 a carburetting apparatus mounted therein and adapted to so mix the air and gasoline that a mixture of maximum efficiency will be led into the combustion chamber of the motor.

30 Other objects of the invention will be made apparent in the accompanying specification, when read in connection with the drawings forming a part thereof.

In said drawings:

35 Fig. 1 is a longitudinal section taken through a fuel tank embodying my invention.

Fig. 2 is a section on the line 2—2 of Fig. 1.

40 Fig. 3 is a section on the line 3—3 of Fig. 1, and,

Fig. 4 is a detail in perspective, showing a portion of my carburetting apparatus.

Now referring specifically to the drawings, 45 in which like reference characters indicate like parts, throughout the several views, A indicates the usual fuel supply tank of an internal combustion engine, here shown as of rectangular formation, and 1 is an elongation 50 of the engine manifold, extending longitudinally over the top of the tank and closely adjacent thereto. Preferably a hood 1^a encloses the manifold 1, and is spaced therefrom. As shown in Fig. 1, the manifold 1 communicates with the interior of the

tank A, through intakes 2, 3 and 4. Intakes 2 and 4 preferably comprise funnels having neck portions entering the manifold, the flared body portions extending into the tank A, as illustrated. The lower portion of intake 3 corresponds to that of 2 and 4, but the upper portion of intake 3 enters the manifold and is turned backward toward the motor, and a screen 5 is positioned directly in front thereof. The lower portions of intakes 2 and 4 are also covered with screens. It is to be understood that the manifold is provided, at some point in its length, with a butterfly valve 6 to control the flow of the mixture therethrough, and with a safety valve 7 to eliminate danger from backfire.

An air-inlet pipe 8, controlled by an adjustable valve 9, leads into the tank A adjacent one end thereof, a detachable leg 10 being connected to the lower end of the pipe 75 and positioned at the bottom of the tank, extending longitudinally thereof, and secured in position by strap members 10', a strap 8' serving to secure the vertical portion of the pipe 8. A cap 11 is screw-threaded onto the end of the leg 10, being removable for cleaning purposes.

The upper face of the leg 10 of the pipe 8 is provided with a plurality of perforations 12 which are preferably punched outwardly from the metal stock as shown, during the formation of the leg 10, whereby to provide upstanding flanges surrounding said perforations 12.

The interior of the tank A may be said to 90 be divided into compartments B, C, D and E. Compartment B is defined by walls 13, 13', which are imperforate, except as hereinafter referred to; compartment C is defined by the wall of the tank and the walls 13, and by 95 perforated walls 14 and 14'; compartment D is confined by walls 13 and the wall of the tank A, and by perforated walls 15, 15', and compartment E, which is the gasoline reservoir, is provided with a perforated upper 100 wall 16.

Pipes 17, 17 are in communication with the leg 10, and extend upwardly through compartments E, D and C, and are provided with goose-neck nozzles 18 which extend through the walls 13 and into the compartment B, as clearly shown in Fig. 1. The lower end of each pipe 17 is perforated at 17', for the admission of gasoline.

In the compartment B is centrally mount-

ed, on the wall 16, a four sided shed 19 preferably of pyramidal configuration, the apex of which is just below the plane of the nozzles 18, and an aproned plate 20, provided with a plurality of perforations, is mounted on the apex of said shed. Fixed on said plate 20 is a vertically disposed baffle 21 carrying above it a protective hood 22. If desired a flat screen 23 may be provided for the top of the plate 20, as shown in the drawings.

Tubes 24 extend through the plate 16, beneath the shed 19, affording communication between compartments B and E, and each face of the said shed is provided with two perforations 19'. Furthermore, as illustrated in Fig. 2, two perforations 19'' extend through the plate 16 adjacent the base of the shed.

The tank A is of air tight construction and, during the operation of the motor, the valves 6 and 9 being properly adjusted, the aspirations of the motor cause air to be drawn into pipe 10 under a pressure greater than the hydro-static head of the fuel in the pipes 10 and 17, 17, and serve to create a suction in the tank through the intakes 2, 3 and 4, drawing air into the pipe 8 and leg 10, and upwardly through the pipes 17, 17, and also upwardly, through the perforations 12, 12, into the gasoline in the compartment E. During this process gasoline is also entrained into the apertures 17', 17', in the pipes 17, 17, and the mixed air and gasoline is carried upwardly in said pipes and forcibly ejected through the nozzles 18, 18, against the baffle 21. The violent contact of the mixed air and fuel particles against the baffle 21 serves to atomize the mixture, but the hood 22 serves to prevent access of any of the heavier particles through the port 3' into the intake 3, immediately above said hood. Certain of the most minutely atomized, or drier particles however, pass around said hood and enter said intake 3.

In the meantime air is also passing out of the orifices 12 and into and through the main body of gasoline in the tank E, causing said gasoline to become violently agitated, and a certain amount of fuel laden air passes upwardly through the perforations in the plate 16, and through the tubes 24. It will be understood that, in the compartment B, the heavier particles of fuel laden air have passed downwardly through the perforations in the screen 23 and plate 20, and drain downwardly along the sides of the shed 19, gradually becoming lighter in this process. The lightest particles are finally lifted by suction and subsequently pass out through intake 3; the heavier particles continue their downward journey and pass through the perforations 19', in the sides of the shed, or reach the perforations 19'', at the base thereof, where they mingle with other up-

coming fuel laden air, passing through the perforations 19'' or the tubes 24, and either finally are deposited in the gasoline in compartment E, or pass upwardly again and, eventually, out through the intake 3, dependent upon their condition of carburation.

It is to be noted that the perforations in the top and bottom walls defining the compartments C and D, are arranged so that the perforations on the one wall are staggered with respect to those on the other wall. While carburation is taking place in the chamber B it is also going on in the chambers C and D. The air passing through the orifices 12 picks up gasoline in the chamber E and the mixed air and gasoline passes upwardly and is atomized by contact with the plate 16; the lighter particles finally pass through the apertures in said plate 16, and contact the plate 15', in which the perforations are out of line with those in the lower plate, and the same process is carried out during the passage of the fuel laden particles through the plate 14, and finally out through the intakes 2 and 4. In all cases the light particles are retained until they are broken up or rarefied sufficiently to pass out of the intakes. It is through this continuous agitation and separation of the mixed particles of air and gasoline, together with the boiling action caused by the passage of the air through the gasoline in the tank E, and the constant impingement of the mixed particles upon baffles in its upward path, that the production of a fuel of maximum efficiency is possible.

It is to be noted that there is no communication between compartments B and the other carburetting compartments or chambers, and that all the mixture which enters compartment B passes into the manifold through the port 3. Compartments C and D are virtually one chamber, with a perforated baffle wall 15' separating them to break up the mixed particles of air and gas, and permit the lighter particles to finally pass out of the ports 2 and 4, on each side of the compartment B.

The drier gas is produced in the central compartment B, because of the violent impingement of the mixed air and gas globules upon the baffle 21, from the nozzle 18, and the provision of the shed 19, with its downwardly inclined walls which permit slow gravitation of the heavier particles until they become more rarefied.

The tank A is filled through the usual port 25, and may be drained through the pet-cock 26.

Various modifications of the structure herein described may be suggested to those skilled in the art, but my invention covers all embodiments falling fairly within the scope of the appended claims.

I claim:

1. The combination with a manifold of an internal combustion engine, of a fuel tank provided with a centrally disposed carburetting chamber, a carburetting chamber at each end of said tank, and a fuel chamber, an air pipe leading into said fuel chamber and perforated below the fuel level, an intake leading into said manifold from said central chamber, and other intakes leading into said manifold from said end chambers, substantially as described. 70
2. The combination with a manifold of an internal combustion engine, of a fuel tank provided with a fuel chamber in its lower portion, and a plurality of carburetting chambers above said fuel chamber and communicating therewith, comprising a chamber on each end of the tank and a central chamber sealed against said side chambers, a port leading from each said chambers into the manifold, and an air pipe leading into said fuel chamber and perforated below the liquid level therein. 75
3. The combination with a manifold of an internal combustion engine, of a fuel tank provided with a fuel chamber in its lower portion, a carburetting chamber above said fuel chamber, an air pipe leading into said fuel chamber and perforated below the liquid therein, a jet pipe communicating with said air pipe, extending into said carburetting chamber and terminating in a restricted nozzle, a baffle located in front of said nozzle, and a port leading from said carburetting chamber into said manifold, substantially as described. 80
4. The combination with a manifold of an internal combustion engine, of a fuel tank provided with a fuel chamber in its lower portion, a carburetting chamber above said fuel chamber, an air pipe leading into said fuel chamber and perforated below the liquid therein, a jet pipe communicating with said air pipe, extending into said carburetting chamber and terminating in a restricted nozzle, a baffle located in front of said nozzle, a port leading from said carburetting chamber into said manifold, and a hood between said baffle and said port. 85
5. The combination with a manifold of an internal combustion engine, of a fuel tank provided with a fuel chamber in its lower portion, a carburetting chamber above said fuel chamber, an air pipe leading into said fuel chamber and perforated below the liquid level therein, a shed with inclined walls in said carburetting chamber, a baffle mounted on the top of said shed, a jet pipe communicating with said air pipe, extending into said carburetting chamber and terminating in a restricted nozzle directed towards said baffle, and a port leading from said carburetting chamber into said manifold. 90
6. The combination with a manifold of an internal combustion engine, of a fuel tank provided with a fuel chamber in its lower portion, a carburetting chamber above said fuel chamber, an air pipe leading into said fuel chamber and perforated below the liquid level therein, a shed with inclined walls in said carburetting chamber, a baffle mounted on the top of said shed, two jet pipes connected to said air pipe and each extending upwardly and having angled portions entering said carburetting chamber, each portion terminating in a restricted nozzle directed toward said baffle, and a port leading from said carburetting chamber into said manifold. 95
7. The combination with a manifold of an internal combustion engine, of a fuel tank provided with a fuel chamber in its lower portion, a carburetting chamber above said fuel chamber, an air pipe leading into said fuel chamber and perforated below the liquid level therein, a shed with inclined walls in said carburetting chamber, a baffle mounted on the top of said shed, two jet pipes connected to said air pipe and each extending upwardly and having angled portions entering said carburetting chamber, each portion terminating in a restricted nozzle directed toward said baffle, and a port leading from said carburetting chamber into said manifold. 100
8. The combination with a manifold of an internal combustion engine, of a fuel tank provided with a fuel chamber in its lower portion, a carburetting chamber above said fuel chamber, an air pipe leading into said fuel chamber and perforated below the liquid level therein, a shed with inclined walls in said carburetting chamber, a baffle mounted on the top of said shed, two jet pipes connected to said air pipe and each extending upwardly and having angled portions entering said carburetting chamber, each portion terminating in a restricted nozzle directed toward said baffle, a port leading from said carburetting chamber to said manifold, and a hood between said baffle and said port. 105
9. The combination with a manifold of an internal combustion engine, of a fuel tank provided with a fuel chamber in its lower portion, a carburetting chamber above said fuel chamber, an air pipe leading into said fuel chamber and perforated below the liquid level therein, a shed with inclined walls in said carburetting chamber, a perforated plate on the apex of said shed, a baffle mounted on said plate, a jet pipe communicating with said air pipe, extending into said carburetting chamber and terminating in a restricted nozzle directed towards said baffle, and a port leading from said carburetting chamber into said manifold. 115
10. The combination with a manifold of an internal combustion engine, of a fuel tank provided with a fuel chamber in its lower portion, a carburetting chamber above 120
11. The combination with a manifold of an internal combustion engine, of a fuel tank provided with a fuel chamber in its lower portion, a carburetting chamber above 125
12. The combination with a manifold of an internal combustion engine, of a fuel tank provided with a fuel chamber in its lower portion, a carburetting chamber above 130

said fuel chamber, a partition separating said two chambers, an air pipe leading into said fuel chamber and perforated below the liquid therein, a jet pipe communicating 5 with said air pipe and terminating in a restricted nozzle entering said carburetting chamber, a shed with inclined walls mounted on said partition and located in said carburetting chamber, a plurality of apertures 10 in the wall of said shed, a plurality of apertures in said partition at the base of said shed and communicating with said fuel chamber, a baffle mounted on said shed in front of said nozzle, and a port in said carburetting chamber 15 leading into said manifold.

11. The combination with a manifold of an internal combustion engine, of a fuel tank provided with a fuel chamber in its lower portion, a carburetting chamber above said 20 fuel chamber, a partition separating said two chambers, an air pipe leading into said fuel chamber and perforated below the liquid therein, a jet pipe communicating 25 with said air pipe and terminating in a restricted nozzle entering said carburetting chamber, a shed with inclined walls mounted on said partition and located in said carburetting chamber, a plurality of apertures 30 in the wall of said shed, a plurality of apertures in said partition at the base of said shed and communicating with said fuel chamber, a baffle mounted on said shed in front of said nozzle, a port in said carburetting chamber leading into said manifold, 35 and a hood mounted between said baffle and said manifold.

12. The combination with a manifold of an internal combustion engine, of a fuel tank provided with a fuel chamber in its lower portion, a carburetting chamber above said 40 fuel chamber, an air pipe leading into said fuel chamber and perforated below the liquid level therein, a jet pipe communicating 45 with said air pipe and terminating in a restricted nozzle leading into said carburetting chamber, a baffle in said latter chamber in front of said nozzle, a port in the said jet pipe establishing communication 50 between said pipe and the liquid in said fuel chamber, and a port leading from said carburetting chamber to said manifold.

13. The combination with the manifold of an internal combustion motor, of a fuel tank provided with a fuel chamber in its lower portion, a carburetting chamber above 55

said fuel chamber, a wall separating the two chambers, an air pipe leading into the fuel chamber and perforated below the liquid level therein, a jet pipe in communication with said air pipe, and perforated below the liquid level, said jet pipe terminating in a restricted nozzle leading into said carburetting chamber, a perforated shed with inclined walls mounted on said wall and within said carburetting chamber, a baffle carried 60 by said shed and positioned in front of said nozzle, tubes leading from said fuel chamber into said carburetting chamber and beneath said shed, and a port leading from said carburetting chamber to said manifold. 65

14. The combination with the manifold of an internal combustion motor, of a fuel tank provided with a fuel chamber in its lower portion, a carburetting chamber above said fuel chamber, a partition separating the two chambers, an air pipe leading into the fuel chamber and perforated below the liquid level therein, a jet pipe in communication 70 with said air pipe, and perforated below the liquid level, said jet pipe terminating in a restricted nozzle leading into said carburetting chamber, a perforated shed with inclined walls mounted on said partition and within said carburetting chamber, a baffle carried 75 by said shed and positioned in front of said nozzle, tubes leading from said fuel chamber into said carburetting chamber and beneath said shed, said partition having a plurality of perforations at the lower edge 80 of said shed, and a port leading from said carburetting chamber to said manifold. 85

15. The combination with the manifold of an internal combustion engine, of a fuel tank provided with a fuel chamber in its lower portion and a carburetting chamber above 90 said fuel chamber, a wall separating said chambers, an air pipe leading into said fuel chamber and perforated below the fuel level, perforated pipes extending from said air pipe into said carburetting chamber and adapted to mix air and fuel in said fuel chamber and to lead the mixture formed thereby into said carburetting chamber, a shed with inclined walls mounted in said carburetting chamber, and ports in said shed 100 and said wall affording communication between said chambers. 105

In testimony whereof I affix my signature.

CHESTER W. ACKERMAN.
